UNITED STATES PATENT OFFICE.

JAMES A. JACKSON, OF SCHENECTADY, NEW YORK, ASSIGNOR TO GENERAL ELECTRIC COMPANY, A CORPORATION OF NEW YORK.

ELECTRIC-RAILWAY SYSTEM.

Application filed August 26, 1925. Serial No. 52,661.

This invention relates to electric railway systems, particularly alternating current electric railway systems suitable for handling mail, parcels, or freight, in which 5 trains of motor-driven cars are operated automatically without operators or motormen on a normally energized main track to which they are fed from branch tracks, under the control of operators located external to the 10 trains of cars.

The invention has for its object the provision of improvements in electric railway systems of the above character for automatically insuring the safe dispatching of trains 15 of cars from the branch tracks to the main track.

While not limited thereto, the invention is of particular utility when used in an automatic electric railway system of the type 20 described and claimed in the co-pending patent application of Robert H. McLain, No. 751,228, filed November 21, 1924, and assigned to the assignee of my present invention. In the McLain type of automatic railway system, alternating current motor-driven cars are assembled into trains and dispatched from branch loading tracks energized from a variable frequency source to the main track which is normally energized 25 from an alternating current source of relatively high constant frequency.

In such an automatic electric railway system my invention provides automatic means for preventing collisions when trains of cars 35 are fed from the branch tracks to the main track, and also insures against interconnection of the high frequency source normally energizing the main track with the variable frequency source employed in accelerating 40 the trains on the branch tracks when the trains of cars are fed to the main track.

In carrying the invention into effect in an automatic electric railway system of the type described in the above McLain application 45 I provide automatic interlocking switch mechanism for preventing energization of the accelerating sections of the branch track when trains of cars are passing over predetermined sections of the main track. By locating the interlocking switches at proper sections of the main track the possibility of accelerating and feeding a train 50 of cars from the branch track to the main track into the path of an on-coming train of 55 cars thereon is effectively eliminated. Fur-

thermore, in accordance with my invention I provide automatic switch mechanism for disconnecting the power source from the branch track just before the first car of a 60 train fed therefrom reaches the main track. This prevents interconnection of the branch track source with the main track source through the train power conductors regardless of the number of cars in the train.

In the accompanying drawing the single 65 figure diagrammatically illustrates my invention embodied in an automatic alternating current electric railway system having a normally deenergized branch track joining a normally energized main track although the invention is applicable to other types of electric railway systems.

In the drawing the main track M is arranged to carry alternating current motor driven cars from the left to the right and the branch track B joins with the main track as shown. The power conductor T_1 of the main track is normally energized from an alternating current source 10 of relatively high frequency to operate the alternating current motor-driven cars thereon at a relatively high speed. The power conductor T_2 of the branch track B is arranged to be energized from an alternating current source of variable frequency 11 through the electromagnetic switch 12, the manually operated switch 13 and the automatic switch mechanism 14.

The alternating current source of variable frequency 11 in the form shown is of 90 the type described in the previously mentioned patent application of Robert H. McLain, No. 751,228, and comprises an alternating current generator 15 which is driven by a variable speed direct current motor 16. 95 The motor 16 is supplied with power from the direct current supply lines 17 and the speed of the motor is varied by means of the rheostat 18 which is connected in the motor field circuit and arranged for either manual operation or automatic operation by the motor 18^a as will be more fully described in connection with the operation of the railway system. The field winding 19 of the alternating current generator 15 also is energized 100 from the direct current supply lines 17 and the exciting current of the generator 15 is suitably varied through the agency of the field rheostat 20.

The electromagnetic switch 12 is energized 110

from suitable supply lines 21 and is under the control of the several car operated interlocking switches which are located along the main track M to be operated by the cars passing thereover. Each of the car operated switches 22 is biased to the circuit closing position as shown so as to normally energize the electromagnetic switch 12 from the supply lines 21. When any one of these interlocking switches is operated to the open position by a passing car the energizing circuit of the electromagnetic switch 12 is interrupted.

The automatic switch mechanism 14 in the form shown comprises a pair of separately operable electromagnetic switches 23 and 24 which, however, are mechanically interlocked so that when one switch is closed the other switch is prevented from operating to the closed position. The contact 25 of the electromagnetic switch 23 in its upper circuit-controlling position in which it is shown connects the power conductor T_2 of the branch track B to the variable frequency power source 11, while the contact 26 of the electromagnetic switch 24 in its upper position connects the power conductor T_2 directly to the normally energized power conductor T_1 of the main track M. The operating winding of each of the electromagnetic switches 23 and 24 is electrically interlocked with the other switch so that each switch can be energized only when the other switch is in its lower position. The energizing circuits for the operating windings of both of the electromagnetic switches 23 and 24 are under the control of the two-position, parallel-connected interlocking control switches 27 and 28, which are located along the branch track B adjacent to the junction thereof with the main track M. Each of the two-position interlocking switches 27 and 28 is suitably biased to the circuit-closing position in which it is shown and is provided with suitable mechanism for engaging with the cars fed from the branch track B to the main track M to operate the control switches to their other circuit-closing positions.

With the power conductor T_1 of the main track M normally energized from the high frequency source 10 and the control switches 27 and 28 in their respective biased positions in which they are shown, the operating winding of electromagnetic switch 23 is normally energized through a circuit extending from the main track power conductor T_1 through the conductor 31, the operating winding of switch 23, contact 26 of switch 24 in its lower position, conductor 32, and in parallel circuit through the contacts of the control switches 27 and 28 to the track rails which constitute the return conductor for both the main track M and the branch track B. Thus the electromagnetic switch 23 is normally energized and

maintained operated to the circuit-closing position in which it is shown in the drawing.

With the electromagnetic switches 12 and 23 in their respective circuit-closing positions in which they are shown, the power conductor T_2 of the branch track B is energized from the variable frequency source 11 upon closure of the manually operable switch 13. Upon energization of the power conductor T_2 the driving motors of the cars which may be upon the branch track B are operatively energized to move the cars toward the main track M. By operating the rheostat 18 to decrease the field excitation of the motor 16, the speed of the alternating current generator 15 may be gradually increased to increase the frequency of the alternating current supplied to the branch track power conductor T_2 and thereby accelerate the motor-driven cars on the branch track B to approximately the normal running speed of the cars on the main track M.

In case a car, or train of cars, should be accelerated on the branch track B and fed therefrom to the main track into the path of an oncoming car, or train of cars, on the main track, a collision would be inevitable. However, this is prevented in accordance with my invention through the engagement of one of the suitably spaced interlocking switches 22 by the oncoming car or cars on the main track. The resulting opening of the interlocking switch 22 interrupts the energizing circuit of the electromagnetic switch 12 and the latter at once operates to the open position in accordance with its bias. The opening of switch 12 effectively prevents connection of the source 11 to the branch track power conductor T_2 upon closure of switch 13 or serves to disconnect the variable voltage source 11 from the power conductor T_2 of the branch track B and thereby deenergize the driving motors of the cars thereon in case the switch 13 was previously closed. Upon the deenergization of the driving motors of the cars on the branch track the electromagnetic brakes ordinarily associated therewith soon bring the cars to rest. If the rheostat 18 has been operated to increase the speed of the driving motor 16 sufficiently to engage the contact segment 29, an energizing circuit for the operating motor 18^a of the rheostat 18 is established upon the operation of the switch 12 to disconnect the generator 15 from the track power conductor T_2 , the circuit extending from the supply lines 17 through the auxiliary contact 30 with which switch 12 is provided. Motor 18^a at once returns the rheostat 18 to the low speed position.

After the oncoming car on the main track M has passed by each of the interlocking switches 22, these switches return to their respective biased positions and reestablish

the energizing circuit for the electromagnetic switch 12. Upon the resulting closure of switch 12 power then may be supplied from the variable frequency source 11 to the driving motors of the cars on the branch track B to safely accelerate and feed the cars to the main track M. Since the speed of motor 16 has been automatically reduced to the minimum value through operation of the motor 18^a, the frequency of the alternating current generator 15 likewise is reduced to the minimum value preparatory to restarting and accelerating the cars on the branch track B.

As the cars on the branch track B approach the main track M, the first car in the train engages with the control switch 27 and operates the same from the circuit closing position in which it is shown to its upper circuit closing position. This, however, does not interrupt the energizing circuit of the electromagnetic switch 23 so long as the parallel-connected control switch 28 remains in its biased position in which it is shown. Furthermore, operation of the switch 27 to its upper circuit closing position does not establish an energizing circuit for the electromagnetic switch 24 since switches 23 and 24 are so interlocked that the switches cannot be energized simultaneously. However, when the cars on the branch track B engage with the control switch 28 and operate the latter from its biased position to its upper circuit closing position, the energizing circuit of the operating winding of switch 23 is interrupted since both of the track switches 27 and 28 now occupy their respective upper circuit closing positions. Consequently, switch 23 is deenergized and at once returns to the lower circuit closing position, thereby automatically disconnecting the branch track power conductor T₂ from the variable frequency generator 15.

When the lower contacts of switch 23 are closed, an energizing circuit for the operating winding of switch 24 is established which may be traced from the power conductor T₁ through the conductor 31, the operating winding of switch 24, and thence in parallel circuit through the contacts of the control switches 27 and 28 in their upper positions. The switches 27 and 28 are so located along the track that one or the other switch always is engaged by a suitable rack carried by each of the cars even though the other switch is released due to the gap in the operating rack between the several cars composing the train. It will be understood that practical operating difficulties on curves and track switches render the use of a continuous operating rack along several cars of the train undesirable. However, by properly locating the two separately operable switches 27 and 28 along the branch track, the switches may be arranged to be simultane-

ously operated from their biased positions but alternately released as the end of the operating rack on each car is reached by the respective switches. In this way the energizing circuit for the switch 24 is maintained established through one or the other of the track interlocking switches 27 and 28.

The resulting energization of switch 24 operates the contact 26 to directly connect the power conductor T₂ of the branch track B to the power conductor T₁ of the main track M. Thus, as the first car of the train leaving the branch track B reaches the main track M and the current-collecting device on the car engages with the main track power conductor T₁, there is no possibility of interconnection between the variable frequency source 11 and the high frequency source 10 through the train conductors connecting the driving motors of the several cars composing the train. This is due to the fact that the automatic switch mechanism 14 is operated under the control of the car operated switches 27 and 28 to automatically disconnect the variable frequency source 11 from the branch track power conductor T₂, and then connect the latter directly to the main track power conductor T₁ as the trains of cars leave branch track B and pass on to the main track M.

From the foregoing it will be seen that my invention insures the safe dispatching of cars from the branch track B to the main track M, since collisions with oncoming cars on the main track, as well as interconnection between the power source supplying the branch and the main track are effectively prevented.

What I claim as new and desire to secure by Letters Patent of the United States is:

1. The combination with an electric railway system having a normally deenergized branch track joining a normally energized main track, of means including a manually operable switch mechanism for energizing the branch track to feed electric motor driven cars therefrom to the main track, and car-operated interlocking devices located on the main track adjacent said branch track and operatively connected with said energizing means for the branch track for preventing energization of the branch track when cars are passing on the main track.

2. The combination with an electric railway system having a normally deenergized branch track joining a normally energized main track, of manually controlled means including an electrically operated switch for energizing the branch track to feed electric motor driven cars therefrom to the main track, a car-operated interlocking switch located on the main track adjacent said branch track, and connections controlled by said car-operated switch for preventing operation of said electrically operated switch to energize

- the branch track when cars are passing on the main track.
3. The combination with an electric railway system having a branch track and a main track arranged to be energized from separate sources, of automatic means including an interlocking switch located adjacent the junction of the branch track with the main track for preventing interconnection between said power sources when trains of cars are passing from one track to the other.
4. The combination with an electric railway system having the power conductors for adjacent track sections energized from separate supply sources, of means including switch mechanism located at the end of one of said track sections and arranged to be operated by the cars passing therefrom to the adjacent section for automatically disconnecting the power conductor of one section from its supply source while the cars bridge the power conductors of the adjacent sections.
5. The combination with an electric railway system having the power conductors for adjacent track sections energized from separate supply sources, of means including switch mechanism located at the end of one of said track sections and arranged to be operated by the cars passing therefrom to the adjacent section for automatically disconnecting the power conductors of one section from its supply source and connect the power conductor of said one section to the supply source of the adjacent section while the cars bridge the power conductors of the adjacent sections.
6. The combination with an electric railway system having a main track connected to be energized from one source, a branch track connected to be energized from a second source, of means including switch mechanism located adjacent the junction of said tracks and arranged to be operated by the cars passing from the branch track to the main track for automatically disconnecting the branch track from said second source and thereby prevent interconnection of said sources through the cars passing from the branch track to the main track.
7. The combination with an electric railway system having a normally energized main track and a branch track connected to be energized from a separate supply source of differing electrical characteristics, of electrically operated switch mechanism for controlling the connection of the branch track with said separate source, a car-operated control switch mechanism located along the branch track adjacent the main track to be operated by the cars passing from the branch
- track to the main track, and connections controlled by said car-operated switch mechanism for effecting operation of said electrically operated switch mechanism to disconnect the branch track from said separate source while the cars bridge the main track and the branch track.
8. The combination with an automatic alternating current electric railway system having a main track normally energized from an alternating current source of relatively high frequency, a branch track arranged to be energized from an alternating current source of variable frequency, an electromagnetic switch mechanism operable to disconnect the branch track from said variable frequency source and connect the branch track to the source of relatively high frequency, a car-operated control switch located along the branch track adjacent the main track, and connections controlled by said switch for effecting operation of said electromagnetic switch mechanism to disconnect the branch track from the variable frequency source and connect the branch circuit to the high frequency source while the cars passing from the branch track to the main track bridge the two tracks.
9. The combination with an electric railway system having a branch track joining a normally energized main track, of means for energizing the branch track from a separate source to feed electric motor driven cars therefrom to the main track, and means including car-operated control mechanism located along the branch track for disconnecting said separate source therefrom while cars are passing on the main track and while cars are entering upon the main track from the branch track.
10. The combination with an electric railway system having a normally deenergized branch track joining a normally energized main track, of manually controlled means including electrically operated switch mechanism for energizing the branch track to feed cars therefrom to the main track, a car-operated interlocking switch located on the main track adjacent said branch track, a second car operated interlocking switch located on the branch track adjacent said main track, and connections separately controlled by said interlocking switches for preventing operation of said electrically operated switch mechanism to energize the branch track when cars are either passing on the main track or cars are entering upon the main track from the branch track.
- In witness whereof, I have hereunto set my hand this 25th day of August, 1925.
- JAMES A. JACKSON.
